EDUARDO MURPHY AND AMERICO ANZULOVICH, OF BUENOS AIRES, ARGENTINA.

BORING-MACHINE.

1,283,542.

Specification of Letters Patent.

Patented Nov. 5, 1918.

Application filed July 17, 1917. Serial No. 181,161.

To all whom it may concern:

Be it known that we, EDUARDO MURPHY, a subject of the King of Great Britain, and AMÉRICO ANZULOVICH, a citizen of the Argentine Republic, residing at No. 1960 San Eduardo street, Buenos Aires, Argentine Republic, have invented certain new and useful Improvements in Boring-Machines, of which the following is a specification.

10 This invention relates to a boring device and has for its object the construction of an apparatus adapted to operate in a perfect and automatic manner.

In order that the invention may be clearly understood and employed without difficulty, 15 an embodiment of this boring device is shown, by way of example, in the illustrative drawings attached wherein:—

Figure 1 is a central section of the drill, 20 showing the principal parts of the same.

Fig. 2 is a similar view of the upper part of the device, illustrating a different position of the locking knives.

Fig. 3 is a horizontal section on the line 25 3 of Fig. 1.

Fig. 4 is a similar section on the line 4.

Fig. 5 is another similar section on the line 5 of Fig. 1, and

Fig. 6 is a similar section on the line 6 of 30 said Fig. 1.

In all the figures, the same numbers of reference indicate the same or corresponding parts.

The borer in accordance with this invention, 35 consists of a cylindrical tube or barrel 1, open at its lower end and having a closed, hemispherical top, provided with a cap or plug 5, adapted to rotate with respect to the barrel 1. The entire borer is suspended 40 from a crane or from some other suitable point, as will be explained later on, by means of a rope 2, fixed outside of the borer to a rod 4 which passes through the plug 5 to which it is firmly fixed by means of a 45 pin, or other suitable fastening. The rod 4 is provided at its lower end with a stirrup 6 which supports a ball bearing 7, arranged below the head 8 of another rod 9. The descending movement of the rod 4 within the 50 barrel 1 is limited by a horizontal division

10 on which is supported the plain face of the stirrup 6.

The lower end of the rod 9 is jointed to two arms 11, jointed in turn to the lower ends of two crescent shaped knives 12, 55 jointed at their upper ends to the lugs 13, affixed to the lower side of the partition 10. Said crescent shaped knives 12 are adapted to close into and to protrude from the barrel 1 through the side slots 14, for a purpose which will afterward be explained. On the rod 9, near the point where the same is jointed to the arms 11, is provided a projection 15, to support the lower end of a spring 16 the upper end of which touches the lower 60 surface of the partition 10. The object of said spring is to keep the stirrup 6 under normal conditions in touch with the upper surface of the partition 10 and as a result to hold the arms 11 in their extended position, with the knives 12 protruding out of the metallic barrel or casing.

Below the said knives is arranged, inside the barrel 1, another horizontal partition 17 which forms the roof of the tubular chamber or casing intended to contain the driving mechanism. Another partition 18, some distance farther down inside the barrel 1, closes the chamber from below, thus preventing the entrance of moisture, earth or 75 other foreign matter, liable to affect the operation of the borer. The wall of the barrel 1, at the section corresponding to the driving gears, is constructed with a door 20, hinged at 21 and adapted to be closed by 80 means of screws at 22 (see Fig. 5). This door allows of access to the motor 19, mounted within the upper part of said chamber and supplied with electric current in the 85 manner to be described.

On the lower end of the shaft of the motor is mounted a gear wheel 23 which engages with another gear wheel 24, fixed to one end of an axle 25, mounted in ball bearings 26, 26. On the other end of the latter 90 shaft is mounted the cog-wheel 27, engaging with a similar wheel 28 fixed to a shaft 29 which holds a position corresponding to the axis of the barrel 1. This latter shaft rotates in ball bearings 30 and is held in po- 95 100

sition at its free end by a socket with ball bearings 31, mounted on a horizontal partition. On the partition 18 is also mounted a packing gland 33 which surrounds the 5 shaft 29 and prevents the passage of moisture and earth.

Although a specific system of driving gear has been described, it will be evident that as the only purpose of the gears is to reduce 10 the speed of the motor to a degree suitable for the drill, any other convenient means of driving may be employed for the same purpose.

Below the partition 18 and in consequence 15 outside the chamber containing the motor and the driving gears, the shaft 29 ends with a boring chuck 32 or other suitable similar device by means of which the cylindrical drill 35 or the like may be fixed in position. The borer or drill is formed by a yoke 34 to which is secured a hollow cylindrical body 35, provided at its lower end with the usual teeth 36 and 37, the teeth 37 being connected by a bridge 38 provided at 20 a point corresponding to the axis of the barrel 1, with a pin or point 39 which guides the device in its operation and supplies a support for the boring tool.

The portion of the barrel 1 occupied by 25 the drill, is provided with a door 51, adapted to be locked in position by means of screws as at 52; in this case, hinges cannot be used on account of the boring tool rotating in close proximity to the inner wall 35 of the barrel.

Electric current is supplied to the motor 19 from any suitable source, not shown in the drawings, by means of a lead 3, ending in a metallic conducting disk 49, separated 40 from the plug 5 by means of an insulating washer 48. Said disk 49 is constantly in contact with a contact piece 50 from which the current is led to one of the terminals of 45 the motor casing. The other terminal of said switch is connected to the motor. Electric contact is established normally in the switch.

In the interior of the drill 35 is arranged 50 a horizontal disk 40 supported by a rod 41 inserted in the shaft of the yoke 34 of the drill or borer. Between the neck of said yoke and the top of the disk 40 is arranged a spring 42 the effect of which is to maintain said disk in its lowermost position. The rod 41 is provided with a lateral stud, adapted 55 to slide within an elongated aperture in the shaft of the yoke piece 34 and supporting a metallic disk 43; this latter rotates with the boring tool 35 and in turn is held 60 fast between two stops 44, affixed to the lower end of a rod 45, this latter being movably connected by means of a pivoted link 46, to the switch 47. When for any

reason as for instance, when the boring tool 65 35 has become filled with earth, the disk 40 rises, it will cause the disk 43 to rise also, and in consequence, the rod 45 and link 46 will break the contact in the switch, whereupon the motor is left without current and 70 stops operating.

Having now substantially described the main parts of the apparatus in accordance with this invention, we shall proceed to explain the method of operation.

The borer is suspended from a crane, not represented, by means of a rope 2 which, as also the electric lead, is arranged to wind up when the boring tool is hoisted. When the boring device is suspended by the rope 80 2, the knives 12, by the action of the connecting arms 11 and the special suspension device, will close into the barrel 1, by the slots 14, and take the position shown in Fig. 2.

After boring has been initiated, as soon as the point 39 of the rotary boring tool 35 rests on the bottom of the bore hole, the drill will no longer exert any strain on the rope 2 and the knives 12, under the pressure 90 of the spring 16, will open outward as indicated in Fig. 1, and sink into the earth on the sides of the bore hole thereby preventing any rotary movement of the barrel 1 with respect to said bore hole.

The boring tool is thus placed in position ready for operation. By means of a switch, (not shown) the motor 19 is then started and through the gears 23—24, shaft 25 and cog-wheels 26 and 27, the shaft 29 which 100 is fixed to the drill 35, is caused to rotate. The drill, as it continues boring, will become filled with earth or sludge, to the level of the disk 40, whereupon the current is cut off from the motor, in the manner heretofore explained. By means of the crane which operates the rope 2, the borer is then extracted; as soon as the boring tool is lifted the knives 12 will again close into the barrel 1, contrary to the action of the spring 110 16, as will be clearly understood on inspecting the drawings.

The stopping of the motor may be noted by the attendant by means of an ammeter or any other suitable known device.

After the boring device, has been hoisted, the door 51 is opened and the earth contained in the boring tool 35 is discharged. The door 51 is then closed again, the crane is put in operation and the borer is lowered 120 into the bore hole. When it comes to rest on the bottom of the same, the knives 12 will open out and the motor commence to work and this series of operations will be repeated until boring has been completed.

In order to avoid any twisting of the cable 2 and the electric lead 3, the former is provided with a ball bearing connection, while

the latter is affixed to and in electric contact with a conducting disk 49, adapted to rotate independently of the barrel 1, and in constant electric contact with the contact piece 50, in the manner heretofore explained.

The arrangement of the interrupting switch 47 and its accessory parts and connections is intended to prevent the boring tool 35 from continuing to rotate after it has become filled with earth, as otherwise serious damage might be caused both to the tool and to the motor 19.

The boring tool 35 is so constructed as to permit of its being dismounted and replaced by a bit when this is necessitated by the stony nature of the soil to be bored, it being well known that cylindrical drills can only be used when working in soft earth or gravel, and that a bit must be used for boring stone or very hard limestone.

A rotary file might also be secured to the shaft 29 for the purpose of widening the bore hole when this is desired as for instance, for the insertion of pipes.

The part of the apparatus corresponding to the motor, is inclosed as before stated, within a chamber or casing formed by the walls of the barrel 1 and the partitions 17 and 18, so as to entirely exclude the entrance of sludge or water which might affect the perfect operation of the motor. For repairing or inspecting the motor, a door 20 has been provided, and this door can be tightly closed by using a packing of asbestos or other suitable material. The driving gears might also be inclosed, if so desired, in an oil casing or be provided with other suitable lubricating means.

Various changes in detail of construction and arrangement will readily occur to those skilled in the art which do not depart from what we claim as our invention.

We declare that what we claim as new and desire to secure by Letters Patent, is:—

1. A boring device, comprising in combination: a cylindrical barrel or tube, open at its lower end, an electric motor contained in said barrel, electric connections from without to said motor, a cylindrical drill or bit, arranged inside the lower part of the barrel, with its lower end slightly protruding beyond the same, means for driving said tool from the motor, means for interrupting the operation of the motor when the cylindrical boring tool becomes filled with earth, and crescent shaped knives arranged to protrude through the walls of the barrel when the boring tool comes to rest on the bottom of the bore hole and which automatically withdraw within said barrel when the boring tool is suspended, substantially as described and for the purpose set forth.

2. In a boring device of the construction recited in claim 1, doors in said outer barrel

or casing arranged opposite the motor and tool respectively, and means confined within the area of said casing for holding said doors in position.

3. A boring device, of the kind as set forth, having a series of crescent shaped knives, destined to lock the device against rotation, with respect to the walls of the bore hole, said knives being pivoted at one end to a fixed part of the apparatus, and a rod jointed to the other end thereof and adapted to slide in a vertical direction, a spring which tends to maintain the knives normally in their operative or open position, the rod being so arranged as to draw the knives in, or render them inoperative, contrary to the action of the spring, on traction being applied thereto by the means which bring about the suspension of the borer, substantially as described and for the purpose set forth.

4. In a boring device of the construction recited in claim 1, a plug freely swiveling in the head of the casing and centrally pierced to permit the passage of a suspension member therethrough, a contact ring mounted on the inner face of said plug, a cable passing through said plug and electrically connected to the contact ring thereon, a brush contact mounted on the inner face of said casing and bearing on said terminal ring, and electrical connection from said brush to the motor.

5. In a boring device of the character described, a casing, a boring tool at the lower end thereof, a motor within the casing, a driving connection between said motor and boring tool, an electric switch in the motor circuit, and means associated with said boring tool for opening the switch when a predetermined amount of work has been done by the tool.

6. In a boring device of the type described, a casing, a motor within the casing, a chambered boring tool driven by the motor, an electric contact device within the casing, and means associated with the boring tool for operating said contact device when the chamber of the boring tool is substantially filled with material.

7. In a boring device of the type described, a casing, a contact device therein, a chambered boring tool within said casing, and means associated with said tool for operating said contact device when the chamber of said boring tool is substantially filled with material.

8. In a boring device of the type described, a casing, a compartment within said casing sealed against the entry of dirt and moisture, a contact device within said compartment, a chambered boring tool located below said compartment, and means associated with said boring tool for operating

said contact device when the chamber of the tool is substantially filled with material.

9. In a boring device of the type described, an electric contact device, a chambered boring tool, a movable diaphragm in the upper portion of the chamber of said boring tool, said diaphragm being displaceable by the material entering said chamber when the latter is substantially filled, and

means associated with said diaphragm for 10 operating said contact device.

In testimony whereof we affix our signatures.

EDUARDO MURPHY.

AMÉRICO ANZULOVICH.
